UNITED STATES PATENT OFFICE.

CHRISTIAN HEILRATH, OF SACRAMENTO, CALIFORNIA.

ADJUSTABLE SHADE-BRACKET.

SPECIFICATION forming part of Letters Patent No. 784,490, dated March 7, 1905.

Application filed June 24, 1904. Serial No. 214,049.

To all whom it may concern:

Be it known that I, CHRISTIAN HEILRATH, a citizen of the United States, residing at Sacramento, in the county of Sacramento and State of California, have invented a new and useful Adjustable Shade-Bracket, of which the following is a specification.

The invention relates to improvements in adjustable shade-brackets.

10 The object of the present invention is to improve the construction of window-shade brackets and to provide a simple, inexpensive, and efficient one of great strength and durability adapted to be attached to a window frame or casing by a single fastening device and capable of ready adjustment to suit shade-rollers of different lengths without changing the fastening device, whereby the injury to window frames or casings resulting from the 15 frequent changing of fastening devices is prevented.

20 A further object of the invention is to provide a device of this character in which the means for adjustably securing the bracket to a window-frame will be concealed beneath or 25 behind the shade-roller.

With these and other objects in view the invention consists in the construction and novel combination and arrangement of parts 30 hereinafter fully described, illustrated in the accompanying drawings, and pointed out in the claims hereto appended, it being understood that various changes in the form, proportion, size, and minor details of construction 35 within the scope of the claims may be resorted to without departing from the spirit or sacrificing any of the advantages of the invention.

In the drawings, Figure 1 is a perspective 40 view of an adjustable shade-bracket constructed in accordance with this invention and illustrating the arrangement of the parts when the bracket is clamped against the window-frame.

Fig. 2 is a longitudinal sectional view of the 45 same. Fig. 3 is a transverse sectional view. Fig. 4 is an elevation, the cam-lever being arranged for releasing the bracket. Fig. 5 is a perspective view of the bracket, illustrating the construction of the slotted arm. Fig. 6 50 is a detail perspective view of the cam-lever.

Fig. 7 is a detail view illustrating the construction of the wedge-shaped head of the cam-lever.

Like numerals of reference designate corresponding parts in all the figures of the drawings.

1 designates an adjustable shade-bracket adapted to support one end of a shade-roller in the usual manner and provided with an inwardly-extending arm 2, forming a base-plate 60 and adapted to fit against the top of a window-frame 3 in the ordinary manner. The arm 2 is arranged horizontally and extends inwardly from the bracket, so as to lie beneath or behind the shade-roller when the latter is in 65 position, whereby the means for adjustably mounting the bracket on the window-frame will be concealed by the roller. The arm 2 is provided with a longitudinal slot 4 to receive a screw 5 or other fastening device for 70 mounting a cam-lever 6 on the window-frame. The screw passes through the slot 4, and the bracket is capable of longitudinal adjustment, as will be readily understood. The cam-lever is provided at one end with a circular head 7, 75 which is bent transversely to form a substantially wedge-shaped head, the engaging face of which presents an intermediate apex and oppositely-inclined side faces. The head of the lever is provided with a central opening 80 to receive the screw, and it is adapted to be partially rotated thereon to arrange the apex of the head either longitudinally or transversely of the arm of the bracket. When the apex is arranged transversely of the arm 85 of the bracket, as illustrated in Figs. 1 to 3 of the drawings, the arm is forced into engagement with the window-frame and is firmly clamped against the same. In this locking position the cam-lever extends longitudinally of the arm and of the shade-roller and is concealed beneath and behind the latter. When the arm is swung downward to a vertical position, as illustrated in Fig. 4 of the drawings, the apex of the head is arranged 90 longitudinally of and extends into the slot of the arm, whereby the latter is released and is capable of adjustment to move the bracket inward and outward to enable it to be properly positioned to receive a shade-roller.

In order to enable the arm or base-plate of the bracket to be firmly engaged with the window-frame, the side portions at opposite sides of the slot are grooved or bowed transversely 5 at their inner faces to present inner concaved faces and to provide longitudinal engaging side edges 9, which are firmly embedded in the window-frame when the lever is in its locked position. By grooving the inner faces 10 of the side portions of the arm the body of the metal is offset from the plane of the side edges, and each side is provided with a pair of longitudinal gripping edges, which are partially sunk into the window-frame. By this construction 15 the bracket is effectually prevented from accidentally slipping. The end portion 10 of the arm is similarly grooved or bowed to provide engaging edges.

The adjustable shade-brackets are designed 20 to be constructed in pairs, one of the brackets being designed to be provided with an ordinary circular opening to receive the journal at one end of the shade-roller and the other being slotted, as illustrated in the accompanying 25 drawings, to receive the journal which is connected with the spring of the roller.

Having thus fully described my invention, what I claim as new, and desire to secure by Letters Patent, is—

30 1. An adjustable shade-bracket having a slotted arm, said arm being provided at opposite sides of its slot with projecting longitudinal edges arranged in pairs, a fastening device arranged in the slot, and means pivotally 35 mounted on the fastening device for engaging

the arm to force the said edges into the supporting-surface, said means being also arranged to release the arm for adjusting the bracket.

2. An adjustable shade-bracket provided with an arm having a slot, a fastening device 40 arranged in the slot, and a cam-lever pivoted on the fastening device and having a substantially wedge-shaped head arranged to be turned transversely or longitudinally of the slot to clamp and release the bracket. 45

3. An adjustable shade-bracket provided with a slotted arm having projecting edges at opposite sides of the slot, a cam-lever provided with a head bent to form an approximately wedge-shaped portion, and a pivot 50 passing through the head and through the slot of the arm, whereby the head is adapted either to extend into the slot or engage the arm at opposite sides of the same.

4. An adjustable shade-bracket provided 55 with an arm having a slot, a lever provided at one end with a head having an approximately wedge-shaped portion, and a pivot passing through the head and through the slot of the arm to permit the head to be turned longitudinally or transversely of the arm, said lever being disposed longitudinally of the arm when the head is in engagement with the same.

In testimony that I claim the foregoing as my own I have hereto affixed my signature in 60 the presence of two witnesses.

CHRISTIAN HEILRATH.
